UNITED STATES PATENT OFFICE.

WILLIAM AITKEN, OF LONDON, ENGLAND.

TELEPHONE SYSTEM.

1,221,404.

Specification of Letters Patent. Patented Apr. 3, 1917.

Application filed July 18, 1913. Serial No. 779,770.

To all whom it may concern:

Be it known that I, WILLIAM AITKEN, residing in London, England, have invented certain new and useful Improvements in Telephone Systems, of which the following is a specification.

My invention relates to common battery telephone systems and more particularly to common battery telephone systems of the manual or semiautomatic type in which cords are used for interconnecting, and has for its objects the giving of the equivalent of instantaneous disconnection and the instantaneous making idle of the called and calling lines by either one or both substations replacing the receiver, so that both lines will be instantly available for a call from any other subscriber and either line may instantly, after replacing the receiver or flicking the switch-hook, make a second call on his particular line lamp.

My invention will be fully understood from the following description taken in connection with the accompanying drawings which illustrate methods of carrying the invention into effect, and in which:—

Figure 1 illustrates a cord circuit with an electromagnetically controlled key to operate in connection with a standard line circuit.

Fig. 2 shows a cord circuit using a relay to perform the same functions as the arrangement shown in Fig. 1.

Fig. 3 shows one method of working over a junction line between two exchanges.

Fig. 4 shows one form of combined auto-disconnection speaking and ringing key.

Fig. 5 shows a cord circuit using a relay as in Fig. 2, but with a modified supervisory system and circuits differing somewhat and the supervisory means, and

Fig. 6 shows another method of working over a junction line between two exchanges, the supervisory system differing from that shown in Fig. 3.

Referring to Fig. 1 a line circuit of a well-known type is shown in which J is an answering jack, J' one of a series of multiple jacks, L a calling lamp, C a line relay which may have an inductive and a non-inductive winding controlling the lamp L, and A a cut-off relay to open the circuit of the line relay, the winding being in parallel with the meter coil M. At the substation there is

shown the telephone set comprising a microphone 1, receiver 2, switch-hook 3, bell 4, and condenser 5 to prevent continuous current flowing through the bell. The cord circuit comprises a disconnecting key K controlled by the electromagnet D. It will be noticed that all the conductors from the plugs P and P' are insulated on the springs 6, 7, 8, 9, 10 and 11 normally. The electromagnet D takes the place of the supervisory relay in one conductor of the answering cord P. The key K is linked to a speaking key Q so that when the key Q is pushed forward to connect up the operator's telephone circuit comprising a condenser 12, receiver 13 and induction coil 14, the extension 15 of the key Q causes it to push forward also the lever K to join all the cord conductors through to the associated cord apparatus, and when current passes through the winding D the lever K is held over by the armature 16. A non-inductive resistance 17 is placed in parallel with the winding of the electromagnet D to prevent cutting down of the speech efficiency. The usual meter key 18 is provided to operate the meter M and the meter M'. A four wound repeater F with a battery B divides the cord circuit into sections for signaling purposes, but allows speech waves to pass freely. The usual supervisory relay 19 with its non-inductive shunt 20 is under the control of the called subscriber. The relay 19 controls a supervisory lamp L', and a lamp L² is provided to indicate when the automatic disconnection of the cords has been effected by the receiver at the calling station being replaced. The lamp L² is only provided when the return of the lever K to the normal position is not considered sufficient, this circuit being controlled by the contacts 21 and 22 and a socket contact 23 controlled by the plug P' or by the speaking key as hereinafter described in connection with Fig. 2. Other details of the cord circuit will be described when considering the operation of the circuit.

Fig. 2 shows a cord circuit in general very similar to that shown in Fig. 1, the main difference being in the use of a relay to control the disconnection of the cords instead of a key. Extra contacts 30, 31 and 32 are fitted on the speaking key Q' of this circuit to control the disconnection supervisory lamp L³ in conjunction with a relay H.

Fig. 3 illustrates my invention applied to junction working. The jack at the outgoing end of the junction is shown at J^2 with the plug P^2 of an A operator's cord equipment. A plug P^3 terminates the incoming junction at another exchange. The new disconnecting relay D' is introduced to keep the cord conductors normally open but closed while the junction is in use for a connection. A four wound repeater F' is provided with windings 33 and 34 connected through the condenser 35 and the windings 36 and 37 with the battery B' between. A high resistance relay N is connected with its high resistance winding 38 across the condenser 35. The relay N also has a low resistance winding 39 on the same core controlled by the called line supervisory relay 40 in such manner as to give the distant operator full supervision of the connection. The relay T connects up the tertiary winding of the operator's circuit for testing purposes and when energized joins the tip conductor of the plug P^3 through. The clearing lamp L^4 is under the control of the distant operator by means of the relays N and 41. The relay 41 also controls the disconnect relay D' . J^3 is a jack of a called line the associated apparatus being similar to that described in connection with Fig. 1.

Fig. 4 shows one form of combined key for disconnecting, speaking and ringing. Two keys K and Q are fitted on a T shaped section of metal 50, the key K on the left being the disconnect key and that on the right the speaking key. The latter key Q has movement in two directions that toward the straight springs being for ringing and that toward the angled spring for speaking. In taking up this latter position the handle by the extension 15 forces over the handle or lever K so that the roller K' presses the springs 51 and 52 against the springs 6 and 7 respectively. In line with these are two other similar sets of springs making up the combination shown in Fig. 1. The electromagnet D has two suitably curved pole pieces 53 to engage with the iron roller K' when the lever K is pushed to the left. When the lever Q is returned to the normal or to the ringing positions the lever K does not follow but is retained by the magnet D when energized, and when the circuit of the latter is opened it returns to normal or vertical position which may be sufficient indication that the plugs may be withdrawn, or this may be supplemented by a lamp signal as already mentioned.

The operation of the circuits of the system shown in Fig. 1 is as follows: When the receiver 2 is lifted to make a call a circuit is completed from battery B^2 through the inductive winding 60 of relay C , contacts 61 and 62 of relay A over one side of the line 65 to switch-hook 3, contact 64, receiver 2, mi-

crophone 1, over the other side of the line, contacts 65 and 66 of relay A , non-inductive winding 67 of relay C to the other side of the battery. The relay C completes a circuit through the lamp L , through contacts 68 and 69 and the lamp glows. The operator answers and learns the caller's requirements by inserting plug P in jack J and throwing over key Q which also carries with it key K . A circuit is then completed from battery B , 75 resistance 70, contacts 51 and 6 of key K , sleeve 71, of plug P , bush 72 of jack J , winding of relay A to earth. The relay A energizes and cuts off the line relay C and the lamp L ceases to glow. The talking circuit 80 is then as follows: from battery B , winding 73 of repeater F , contacts 74 and 8 of key K , tip 75 of plug P , spring 76 at jack J over line and telephone at the calling station as before described to spring 77 of jack J , ring 85 78 of plug P , contacts 7 and 52 of key K , winding of electromagnet D with the shunt 17 in parallel with it, winding 79 of repeater to the other side of the battery B . Electromagnet D is energized and its armature 16 holds the key K so that contacts 51 and 6, 52 and 7, 74 and 8, 80 and 9, 81 and 10, 82 and 11, 21 and 22 are made and retained so long as current passes through the coil D . The operator's circuit is completed in the well-known manner by throwing over key Q through contacts 90 and 91 and 92 and 93 of key Q , connecting it across the windings 94 and 95 of repeater F . When the operator brings the key Q to the through or ringing 100 positions, key K does not return with it. The plug P' is then inserted in the jack of the line wanted corresponding to jack J' , when a circuit is completed from battery B , resistance 96, lamp L' , contacts 80 and 9 of key K to sleeve 97 of plug P' , then by a circuit corresponding to bush 98 of jack J' and winding A to earth. The talking circuit is from battery B , winding 94 of repeater F , contacts 99 and 100 of key Q , contacts 82 and 11 of key K , tip 101 of plug P' over the line as already described to ring 102 of plug P' , contacts 10 and 81 of key K , contacts 103 and 104 of key Q , relay 19 and winding 95 of repeater F to the other side of the battery B . The relay 19 by the contacts 105 and 106 shunts out lamp L' by resistance 107 when the subscriber answers, the relay 19 not energizing when the plug is first inserted owing to the condenser at the called station 120 keeping the circuit open.

The replacing of the receiver 2 after conversation will open the calling line circuit by introducing a condenser 5 in series with a bell 4. The magnet D will be deenergized 125 and the key K will return to the vertical position to indicate to the operator that the plugs must be withdrawn. The key K will open the circuit of all the conductors of the cords so that the relay A will deenergize 130

and connect up the line relay C and battery B² so that if the receiver is immediately again lifted the lamp L will glow and an alarm controlled by a relay in series with it in a well known manner, will respond. The opening of the contacts 51 and 6 of key K will also remove current from the test wire connecting all the springs 72 of the jacks J together, so that immediately the receiver 2 is replaced and the operator desires this line for another call, it will test idle. Should the operator be very busy she may delay removing the plugs without the slightest fear of retaining the lines engaged. Should the return of the lever to the vertical position not be considered a sufficient signal, this may be supplemented by a lamp L². When the magnet D released, the key K and contacts 21 and 22 were closed and completed a circuit from battery B, lamp L², contacts 22 and 21 of key K, contacts 110 and 23 of plug socket contact to earth. The lamp L² therefore glows. The plug socket contacts 110 and 23 may be replaced by contacts on the speaking key as will be described hereinafter for Fig. 2. The called subscriber controls the supervisory lamp L' in the well known manner, this being shunted out when the receiver is off the switch-hook and glowing when on the hook. The operator may cause the meters M and M' to register either before or after the receiver 2 is replaced by depressing a key 18, the circuit in the latter case being from battery B, supplementary battery B³, winding of meter M', contacts 111 and 112 of key 18, sleeve 71 of plug P, bush 72 of jack J, winding of relay A and winding 112 of meter M in parallel to earth. The meter M' registers after the meter M, when the resistance of the circuit has been reduced by the armature of M bringing in the front winding 113.

Referring to Fig. 2, the cord circuit shown therein operates generally in a manner very similar to that shown in Fig. 1. When the operator inserts a plug P⁴ and pushes over key Q' (to the left with reference to Fig. 4) to answer a call, the circuit is completed from battery B⁴, winding 120 of magnet D², contacts 31 and 30 of key Q' to earth. The magnet D² is energized and closes all these contacts. When the key Q' is returned to normal or ringing positions the magnet D² is retained energized because a circuit is completed from battery B⁴, winding 121 of repeater F² contacts 122 and 123 of magnet D², tip 124 of plug P⁴, over a circuit described in connection with Fig. 1, back to the ring 125 of the plug P⁴, contacts 126 and 127 of the magnet D², winding 128 of magnet D² with shunt 129 in parallel with it to the winding 130, repeater F² to the other side of the battery B⁴. When the receiver at the calling station is replaced and the circuit opening the magnet D², insulates

all cord conductors and therefore allows the line relay and lamp to come into circuit and also removes the engaging current from the test circuit of the multiple jacks. When the plug P⁴ is in the jack, the third conductor circuit is as follows, from battery B⁴, relay H, contacts 131 and 132 of magnet D, sleeve 133 of plug P⁴, bush of corresponding jack and the cut-off relay to earth. The relay H is energized and completes a circuit through contacts 134 and 135 of relay H, lamp L³, springs 32 and 30 of key Q' to earth. The lamp L³ is shunted out by the winding of the cut-off relay but when the replaced receiver causes the magnet D² to open all the circuits, the relay H remains energized and the lamp L³ glows as a clearing signal. The lamp L³ glowing will indicate idle lines and will either glow until the plugs are brought into use for another connection, or the operator may flick over the key Q' to momentarily open the circuit. These contacts may be made at the plug socket as described in connection with Fig. 1.

Referring to Fig. 3 the invention is shown applied to junction working. When a call is answered as described in connection with Figs 1 and 2 and the line wanted is in another exchange the A operator will pass the call to a B operator in the exchange in which the called line is located, and that operator will allocate the junction line. The A operator will insert the plug P² in an out-going junction jack J² when the circuit will be extended from tip 140 of plug P² to spring 141 of jack J² over the line to the distant exchange, winding 33 of repeater F', high resistance winding 38 of relay N, winding 34 of repeater F', over the other side of the line to spring 142 of jack J² and ring 143 of plug P². The relay N will be energized and complete a circuit from earth, contacts 144 and 145 of relay N, winding of relay 41 to battery B⁵ to earth. The relay 41 in turn will complete a circuit from earth, contacts 146 and 147 of relay 41 winding of relay D' to battery B⁵ and earth. The relay D' will complete circuits when the plug P³ is in jack J³ as follows:—from battery B⁵, winding 36 of repeater F', contacts 148 and 149 of relay D', contacts 150 and 151 of magnet T, tip 152 of plug P³ and over the line circuit as before described to ring 153 of plug P³, contacts 154 and 155 of relay D², relay 40 with shunt 156 in parallel with it, winding 37 of repeater F' to the other side of the battery B⁵.

The B operator prior to inserting the plug P³ tests the line wanted in the well known manner, a circuit being completed from the multi-jed test wire of the line to be connected to by bush of jack 160, tip of plug 152, spring 150 and back contact of relay T, tertiary winding IC of operator's induction coil to earth.

When the plug P^3 is inserted in jack J^3 a third conductor circuit is completed from battery B^5 magnet T , lamp L^4 , contacts 157 and 158 of relay D' , sleeve 159 of plug P^3 , 5 bush 160 of jack J^3 and winding of relay A' to earth. As the relay 41 is energized the lamp L^4 is shunted out by the resistance 161 and contacts 162 and 163 of relay 41. The relay 40 is energized when the receiver is 10 lifted and completes by its contacts a circuit through the low resistance winding 39 of relay N in parallel with the high resistance winding 38, so that the supervisory relay 19 (Fig. 1) is energized, and shunts out the 15 lamp L' and the A operator thus knows that the called subscriber has answered.

When the calling subscriber replaces the receiver after conversation the magnet D de-energizing allows the key K to open all its 20 contacts and thus insulating all the conductors of the plug P' . The relay N is de-energized and its local circuit opens the circuit of relay 41 which opens the circuit of relay D' which insulates all conductors of 25 the plugs P^3 (Fig. 3) and thus removes the busy test from the multiple jacks and allows the line relay C' to join up the line lamp L^4 . The relay 41 also removes the shunt from 30 the lamp L^4 so that it glows as a clearing signal, its circuit being from battery B^5 relay T , lamp L^4 , contacts 158 and 164 of relay D' , contacts 165 and 166 of socket contact to earth. When the plug P^3 is returned to its socket the lamp ceases to glow. 35 Instantaneous withdrawal is not however essential and the lamp L^4 glowing may be taken as a signal that the line is now available for another connection, so that glowing lamps will indicate idle lines. The lines in 40 both exchanges for all practical purposes have been automatically disconnected and restored to normal or calling condition, and perhaps of greater importance the junction line has been made available for immediate 45 further use, instead of waiting the pleasure or leisure of the A operator to withdraw the plugs at her position as at present.

The called subscriber by replacing his receiver de-energizes the relay 40 (Fig. 3) 50 which removes the shunt winding of relay N so that the relay 19 (Fig. 1), opens the shunt about the lamp L' and allows it to glow.

In the specific forms of the invention hereinbefore described supervisory lamp signals have been provided which are caused to glow on the termination of the period of connection. There will now be described arrangements in which a lamp is caused to glow 55 during the period of connection and to be extinguished at the termination of the connection, that is to say, when the plugs become electrically inoperative.

In Fig. 5 a cord circuit is shown similar

to Fig. 2 in that the plug is made electrically 60 inoperative by means of a relay D^3 . L^7 is the supervisory lamp which glows during the period of connection and is extinguished at the termination of the connection. Q^2 is the combined speaking and ringing key, 70 with the speaking part of which magnet D^3 is linked electrically so that when the operator moves the lever to connect her speaking set to answer a call, relay D^3 is energized over the subscriber's line. For this purpose 75 the relay D^3 has three windings, two with battery between being joined across the loop and the other being joined to a contact on the speaking key, the three windings magnetizing the core in the same direction. The 80 lamp L^7 has its circuit completed through contacts on relay D^3 so that it glows so long as relay D^3 is energized. The lamp L^7 is controlled by the relay 170. The relay 170 is double wound with battery connected between the windings and it is connected across the calling cord for supervision purposes and through the windings current is supplied to the called subscriber's microphone. M^2 is the operator's meter controlled by the key 90 171.

It will be seen that the cord circuit in Fig. 5 is arranged on the well-known Stone system with condensers to divide the cord circuit as distinguished from the arrangement 95 shown in Fig. 2 where repeater coils are employed.

The operating and the circuits are described in detail hereinafter.

Fig. 6 illustrates another method of applying the invention to working over a junction line between two exchanges. As in the arrangement shown in Fig. 5 a supervisory lamp (lamp L^8) is caused to glow during 100 the period of connection and is extinguished at the termination of the connection. The supervisory lamp L^8 is controlled directly by the relay D^4 and this arrangement makes it possible to simplify the circuits considerably. The supervisory relay O is shown joined in 110 parallel with the repeater.

The operation of the arrangement shown in Fig. 5 will now be described. To answer a call the plug P^5 is inserted in a jack such as the jack J in Fig. 1 and the speaking key 115 lever pressed back so that contacts 172 and 173, 174 and 175 are closed and the operator's telephone set joined across the cord. At the same time contacts 176 and 178 of the key Q^2 are closed completing a local circuit 120 from battery B^6 , winding 179 of relay D^3 , contacts 178 and 176 of key Q^2 to earth so that relay D^3 is energized and joins all of the conductors through so that circuits are completed from plug P^5 to plug P^3 . The 125 calling lamp ceases to glow as the cut-off relay is energized owing to a circuit being completed from battery B^6 , resistance 180,

contacts 181 and 182 of relay D³, to sleeve 183 of plug P⁵, bush of the jack and winding of cut-off relay to earth.

A circuit is completed over the calling line 5 from battery B⁶, winding 184 of relay D³, contacts 185 and 186 of relay D³, tip 187 of plug P⁵, to one spring of the jack over the line wire through the subscriber's speaking set and back by the other fine wire to the 10 other spring of the jack, ring 188 of plug P⁵, contacts 189 and 190 of relay D³, winding 191 of relay D³ to earth. One side of each 15 of the windings 184 and 191 are connected also to the condensers 192 and 193 so that speech may be transmitted. The operator's microphone is in a local circuit (not shown) of the coil 194 with battery.

Having learned the caller's requirements 20 the operator tests the line wanted by touching 20 the jack of the called line with the tip of the plug P⁶ in the well-known manner and if the line is idle inserts the plug P⁶ when circuits similar to those just described 25 are completed for the called line by contacts 195 and 196 and 197 and 198 of relay D³. Current is fed through windings 199 and 200 of relay 170. The cut-off relay is energized from a circuit from battery B⁶, lamp L⁸, contacts 201 and 202 of relay 170, contacts 203 and 204 of relay D³, sleeve 205 of 30 plug P⁶, bush of jack, winding of cut-off relay to earth. The lamp L⁸ glows until the subscriber answers, when the relay 170 is energized and the lamp circuit broken, it 35 being replaced by the resistance 207. After inserting the plug P⁶ in the jack of the called line the operator moves the lever of key Q² to the ringing position and thereby breaks the circuit of the winding 179 of the 40 relay D³ and this relay is now already energized by the circuit through the caller's speaking set. If now the caller replaces his receiver, the circuit will be opened and the relay D³ deenergized so that it opens the 45 circuit of all the conductors. The lamps L⁷ glowing during the period of a connection may be used as an indication of the operator's load to the supervisor who can then, more readily than with the systems at present in use, take steps for equalizing the load.

The called line is safeguarded against the caller holding up his line by refraining to replace the receiver promptly as the party calling causes the supervisory lamp L⁸ to 50 glow, in these circumstances.

The operation of the arrangement shown in Fig. 6 is as follows:— The A-operator whom it will be assumed, for convenience is provided with cord circuits as shown in 55 Fig. 5, desiring a connection in another exchange asks for it over an order wire and is allotted a junction by the B-operator. The A operator inserts the plug P⁷ (similar to plug P⁶ of Fig. 5) in the jack J⁴, thereby

supplying battery through windings 210 and 65 211 of the repeater F² and winding 212 of relay R. Relay R is energized and completes a circuit from battery B⁷, winding of relay D⁴, contacts 213 and 214 of relay R 70 to earth. Relay D⁴ is energized and joins all the conductors through to the plug P⁸ and also completes the circuit from battery B⁷ through the lamp L⁹, contacts 215 and 216 of relay D⁴ to earth, so that the lamp L⁹ 75 glows and remains glowing so long as the plug P⁷ is in the jack J⁴ and the calling subscriber has not replaced his receiver on the hook.

The B-operator tests the line wanted and if idle inserts the plug P⁸ into the jack of the called line when the induction coil winding 217 of her testing circuit is opened and the tip conductor circuit completed by the action of the third conductor relay 218 in the well-known manner, the circuit to the plug sleeve 219 being completed by contacts 220 and 221 of relay D⁴. Current is supplied to the called line from battery B⁸ windings 222 and 223 of the repeater F² with windings of 80 relay O in parallel, contacts 224, 225, 227 and 226 to tip and ring of plug P⁸ over the line wires and through the speaking set when the receiver is lifted. When the called party answers, relay O is energized and a circuit completed for the low resistance winding 228 of relay R in parallel with the high resistance winding 212. The lowering of the resistance over the junction line causes the supervisory relay of the A operator's 85 cord to be operatively energized, thereby opening the circuit of the supervisory lamp. For example, with the A operator's cord circuit shown in Fig. 5, the relay 170 is energized, opening the circuit of the lamp L⁸. 90

After conversation, when the calling line's 95 speaking set is put out of circuit, relay D³

(Fig. 5) is deenergized and opens all the plug conductor circuits. Relay R is thus deenergized and opens the circuit of relay D⁴ and it in turn opens the circuits of the plug P⁸ so that the engaging battery is removed from the multiplied bushes of the jacks of the line and the line tests instantly 100 idle to another operator. The cut-off relay is also released so that the line lamp is in circuit to indicate another call if the receiver is again lifted, and the plug is inoperative and may remain in the jack until required for another connection. The lamp L⁹ ceasing to 105 glow indicates that the plug is now available 110 for further use. The replacing of the receiver of the calling party thus automatically releases the two lines connected, and restores them to their normal or calling condition 115 and also releases instantly the junction circuit for immediate further use. Again the called line is safe-guarded when the caller does not replace the receiver promptly, as 120 125

if the called line receiver is replaced in this condition the relay O opening the shunt circuit, the relay 170 (Fig. 5) at the A position, will deenergize and the lamp therefore 5 will glow, indicating this irregularity. The lamps L⁷ glowing during connection will indicate to the supervisor the nature of the traffic and the suitability of the junctions provided for the amount of traffic, and they 10 can therefore be loaded to their maximum capacity more efficiently without interfering with the efficiency of the service.

In the foregoing description of the invention as applied to working over a junction line between two exchanges it has been 15 assumed in the case of the arrangement shown in Fig. 3 that the A operator is provided with cords similar to that shown in Fig. 2 and in the case of the arrangement 20 shown in Fig. 6 that the A operator is provided with cords similar to that shown in Fig. 5, but this is not a necessity as the invention can be applied to junction working with any type of cord at the A operator's 25 position.

Various modifications may be made in the method of carrying this invention into effect, the above as applied to manually operated switchboards being given merely by way of 30 example.

For example the invention is applicable to all known common battery circuits whether using repeaters, coils, condensers and relays with or without retardation coils and 35 the like.

Further it will be readily understood by those skilled in the art that the invention can be advantageously applied to semi-automatic switchboards, non-multiple private bank 40 branch boards where the same cords are used for working between two local lines or a local line to a junction or the like.

What I claim and desire to secure by Letters Patent is:—

45 1. In a common battery telephone or like system, the combination of a calling line, a called line, an operator's cord circuit for effecting or completing connection between said calling line and said called line, a plug for said cord circuit and means for opening the conductors connected to said plug to break down the connection and to restore the lines to normal condition upon the talking set of one of the lines being disconnected 50 from said line, all of the circuits of the cord being returned to normal without further operating act.

60 2. In a common battery telephone or like system, the combination of a calling line, a called line, an operator's cord circuit for effecting or completing connection between said calling line and said called line, a plug for said cord circuit and means for automatically opening the conductors connected 65 to said plug to break down the connection

and to restore the lines to normal condition upon the talking set of one of the lines being disconnected from said line, all of the circuits of the cord being returned to normal without further operating act.

70 3. In a common battery telephone or like system, the combination of a calling line, a called line, an operator's cord circuit for effecting or completing connection between said calling line and said called line, a plug for said cord circuit and means for automatically opening the conductors connected to said plug to break down the connection and to restore the lines to normal condition upon the talking set of the calling line being disconnected from said calling line, all of the circuits of the cord being returned to normal without further operating act.

75 4. In a common battery telephone or like system, the combination of a calling line, a called line, an operator's cord circuit for effecting or completing connection between said calling line and said called line, a plug for said cord circuit, conductors in said cord circuit connected to said plug and to springs, and electromagnetic means for separating 80 said springs to open the connection to said plug to break down the connection and to restore the lines to normal condition upon the talking set of one of the lines being disconnected from said line, all of the circuits of the cord being returned to normal without further operating act.

90 5. In a common battery telephone or like system, the combination of a calling line, a called line, an operator's cord circuit for effecting or completing connection between said calling line and said called line, a plug for said cord circuit, conductors in said cord circuit connected to said plug and to springs 95 and electromagnetic means for separating said springs to open the connection to said plug to break down the connection and to restore the lines to normal condition upon the talking set of the calling line being disconnected from said calling line, all of the circuits of the cord being returned to normal without further operating act.

100 6. In a common battery telephone or like system, the combination of a calling line, a called line, an operator's cord circuit for effecting or completing connection between said calling line and said called line, a plug for said cord circuit, a relay, conductors in said cord connected to contacts on said relay 105 and means for automatically operating said relay to open the connection to said plug to break down the connection and to restore the lines to normal condition upon the talking set of one of the lines being disconnected from said line, all of the circuits of the cord being returned to normal without further operating act.

110 7. In a common battery telephone or like system, the combination of a calling line, a 115

called line, an operator's cord circuit for effecting or completing connection between said calling line and said called line, a plug for said cord circuit, a relay, conductors in 5 said cord connected to contacts on said relay and means for automatically operating said relay to open the connection to said plug to break down the connection and to restore the lines to normal condition upon the talking 10 set of the calling line being disconnected from said calling line, all of the circuits of the cord being returned to normal without further operating act.

8. In a common battery telephone or like 15 system, the combination of a calling line, a called line, an operator's cord circuit for effecting or completing connection between said calling line and said called line, a plug for said cord circuit and means for opening 20 the conductors connected to said plug upon the talking set of one of the lines being disconnected from said line, the connection to said plug being normally open.

9. In a common battery telephone or like 25 system, the combination of a calling line, a called line, an operator's cord circuit for effecting or completing connection between said calling line and said called line, a plug for said cord circuit and means for automatically opening the conductors connected 30 to said plug upon the talking set of one of the lines being disconnected from said line, the connection to the said plug being normally open.

35 10. In a common battery telephone or like system, the combination of a calling line, a called line, an operator's cord circuit for effecting or completing connection between said calling line and said called line, a plug for said cord circuit and means for automatically opening the conductors connected 40 to said plug upon the talking set of the calling line being disconnected from said calling line, the connection to said plug being 45 normally open.

11. In a common battery telephone or like 50 system, the combination of a calling line, a called line, an operator's cord circuit for effecting or completing connection between said calling line and said called line, a plug for said cord circuit, conductors in said cord circuit connected to said plug and to springs, and electromagnetic means for separating 55 said springs to open the connection to said plug upon the talking set of one of the lines being disconnected from said line, the connection to said plug being normally open.

12. In a common battery telephone or like 60 system, the combination of a calling line, a called line, an operator's cord circuit for effecting or completing connection between said calling line and said called line, a plug for said cord circuit, conductors in said cord circuit connected to said plug and to springs 65 and electromagnetic means for separating

said springs to open the connection to said plug upon the talking set of the calling line being disconnected from said calling line, the connection to said plug being normally open.

70 13. In a common battery telephone or like system, the combination of a calling line, a called line, an operator's cord circuit for effecting or completing connection between said calling line and said called line, a plug for said cord circuit, a relay, conductors in said cord connected to contacts on said relay and means for automatically operating said relay to open the connection to said plug upon the talking set of one of the lines being 80 disconnected from said line, the connection to said plug being normally open.

75 14. In a common battery telephone or like system, the combination of a calling line, a called line, an operator's cord circuit for effecting or completing connection between said calling line and said called line, a plug for said cord circuit, a relay, conductors in said cord connected to contacts on said relay and means for automatically operating said 85 relay to open the connection to said plug upon the talking set of the calling line being disconnected from said calling line, the connection to said plug being normally open.

90 15. In a common battery telephone or like system, the combination of a calling line, a called line, an operator's cord circuit for effecting or completing connection between said calling line and said called line, a plug for said cord circuit, means for automatically 95 opening the conductors connected to said plug to break down the connection and to restore the lines to normal condition upon the talking set of one of the lines being disconnected from said line, all of the circuits 100 of the cord being returned to normal without further operating act, and means for giving a supervisory signal when the connection through to the plug is broken.

105 16. In a common battery telephone or like system, the combination of a calling line, a called line, an operator's cord circuit for effecting or completing connection between said calling line and said called line, a plug for said cord circuit, means for automatically 110 opening the conductors connected to said plug to break down the connection and to restore the lines to normal condition upon the talking set of the calling line being disconnected from said calling line, all of the 115 circuits of the cord being returned to normal without further operating act, and means for giving a supervisory signal when the connection through to the plug is broken.

120 17. In a common battery telephone or like system, the combination of a calling line, a called line, an operator's cord circuit for effecting or completing connection between said calling line and said called line, an operator's talking set associated with said cord 125 130

circuit, an operator's key associated with said cord circuit, a plug for said cord circuit, conductors in said cord circuit connected to said plug, and normally open in said cord circuit, means for automatically closing said conductors in said cord circuit on the operation of said key to connect the operator's talking set in circuit, and means for opening the conductors connected to said plug upon

the talking set of one of the lines being disconnected from said line.

In testimony whereof I have affixed my signature in presence of two witnesses.

WILLIAM AITKEN.

Witnesses:

WILLIAM S. COLLINS,
H. D. JAMESON.
